IGNITION MECHANISM

Edward B. Nowosielski, Bloomfield, N. J., assignor
to Eclipse Aviation Corporation, East Orange,
N. J., a corporation of New Jersey

Application June 2, 1934, Serial No. 728,793

2 Claims. (Cl. 123—169)

This invention relates to ignition devices for internal combustion engines, and particularly, though not exclusively to ignition devices wherein a heating coil is included for first heating the combustion chamber of an engine to expedite the attainment of ignition temperature, whereupon ignition is produced by means of a jump spark.

An object of the invention is the provision of a novel plug of the type involving the use of a pair of electrodes separated by a small air gap, with one of the electrodes electrically connected to a glow coil of suitable resistance to produce high heat radiation.

Another object of the invention is to provide a plug adapted for the above described purposes and embodying in its construction novel features of practical advantage, including novel means for housing the glow coil so that the coil and the leads thereto are protected from exposure to the products of combustion.

These and other objects and advantages of the invention will be more apparent from the following detailed description, taken in connection with the accompanying drawing wherein two embodiments of the invention are shown. It is to be expressly understood, however, that the drawing is for the purpose of illustration only, and is not designed as a definition of the limits of the invention, reference being had for this purpose to the appended claims.

In the drawing,

Fig. 1 is a longitudinal section through a device embodying the invention;

Fig. 2 is a transverse sectional view along the line 2—2 of Fig. 1; and

Fig. 3 is a longitudinal section of a second embodiment of the invention.

Referring first to the embodiment shown in Figs. 1 and 2, the invention is therein shown as incorporated in a compact, symmetrical unit having a shell portion 5 of current conducting material adapted to constitute the negative electrode of the plug. As shown, the shell 5 includes an upper polygonal portion 6 adapted for engagement by the usual socket type of wrench for attachment of the unit, and a central externally threaded portion 7 adapted to engage corresponding threads cut in a member 8 which, as shown, has an integral extension 9 of sufficient length to receive and enclose substantially the entire length of the lower unthreaded and thinner wall section 11 of the shell. The member 8 may be a part of the engine cylinder or it may be an adapter member attachable to the engine cylin-

der by suitable means adapted to be inserted through the openings 13 and 14.

At its lower end the extension 9 is shown as provided with an inwardly extending portion 16 providing an annular ledge 17 on which a sealing washer 18 rests and is in turn engaged by a flange 19 formed on the section 11 of the shell just above the spherical lower end 21 thereof. Preferably, the lower end 21 is apertured centrally as shown at 22 to permit the lower end 24 of the positive electrode 26 to project therethrough. Just above the lower end 24 the electrode is of a larger diameter, as indicated at 27, and the upper surface of the enlarged portion 21 constitutes a seat and support for a plurality of insulating discs 29 of gradually increasing diameter; the upper discs of the series being separated from the electrode by the interposition of the usual insulating wrapper 31 which surrounds almost the entire length of the electrode 26. A second series of insulating discs 33 surround the upper portion of the insulating wrapper 31, and these are held in assembled relation by the usual cap 36 having its upper surface countersunk as indicated at 37, to receive the upset end 38 of the electrode, while the lower set of insulating discs 29 is held in assembled relation by the provision of a sleeve 41 threadedly engaging the shell 5, as indicated at 42, the head 43 being separated from the head 6 of the shell 5 by suitable means 46.

The parts thus far described will be understood as functioning in the manner of the conventional spark plug to cause a spark to jump across the air gap between the lower end 24 of the positive electrode and the spherical end 21 of the negative electrode which, as indicated, is grounded on the cylinder wall through its contact with the member 8, it being understood that a high tension lead is attached to the cap 36.

There remains to be described the novel manner in which the negative electrode sleeve 11 achieves the double function of conducting the high tension spark current and also the current which is used for the purpose of generating sufficient heat to insure ignition of the initial fuel charge.

As shown, such means includes a coil 49 of current conducting wire having suitable resistance and cross section, and adapted to be wound about an insulating sleeve 51 which surrounds the lower section 11 of the shell 5, one end of the coil being embedded in the electrode 21, as indicated at 53, and the other end being led through a longitudinal groove 54 provided in the outer surface of the upper portion of the shell 5 from which point

the lead 56 extends to a suitable source of current for energization of the coil.

In the embodiment shown in Fig. 3 the adapter 3 of Figs. 1 and 2 is eliminated and in its place there is a threaded extension 60 integral with shell 61 and adapted for attachment to the cylinder wall. Suspended from the sloping inner ledge 62 of the shell is a sleeve 63 terminating in electrodes 64 adapted to receive current, in the usual spark discharge fashion, from central electrode 66, the latter passing through non-conducting core 67 and contacting a cable terminal receiving stud 68 at its outer end. The heating coil 69 surrounds the core 67 and rests upon a metallic washer 70 whose periphery contacts the upper end 71 of the sleeve 63 and thus electrically and thermally connects the coil 69 with the grounded shell extension 60. A lead 73 passing through a radial slot 74 in the insulating sleeve 75 connects the source of current (not shown) with the upper end of the coil, there being sufficient clearance between core 67 and sleeve 75 to permit insertion of this lead. A gland nut 76 holds sleeve 75, coil 69 and washer 70 in place, and completes the assembly.

It will be noted that in both embodiments herein illustrated, the glow coil is effectively sealed and protected from contact with the products of combustion in the cylinder, and as a consequence of this protection there is no danger of breaking down of the insulation separating said coil (and the lead thereto) from the other current conducting parts of the plug. In the form of the invention shown in Fig. 1, the effective seal is assured by the provision of a washer 18 which is preferably made of copper or some material having the ductility and heat conductivity of copper so that the tightening of the nut 6 will insure a firm seating of the washer and prevent seepage of any of the products of combustion into the annular space occupied by the coil 49. A high heat conductivity for the washer 18 is desired in order to provide effective radiation of the heat transferred from the grounded end 53 of the glow coil to the lower end of the extension 9, such heat transfer being to a large extent by way of the washer 18. In the embodiment shown in Fig. 3, the effective sealing of the chamber con-

taining the glow coil 69 is assured by reason of the bend in sleeve 63 and the pressure exerted thereon in a vertical direction by the tightening of nut 76. This pressure seals the plug at this point as well as at the point 78 where the gasket 79 is located.

It will be further noted that in both embodiments there is one electrode common to both the spark producing and glow producing currents. In the embodiments shown in Figs. 1 and 2, this electrode is indicated by the reference character 11 while in Fig. 3 this common electrode is indicated by the reference character 63. In each embodiment this common electrode is disposed in coaxial relationship with the glow coil, it being disposed within said coil in one embodiment, and surrounding said coil in the other. It is to be understood however, as above suggested, that changes may be made in the relative arrangement of parts as well as in other features of construction and the method of installation.

This application is a continuation in part of my co-pending application No. 643,285, filed November 18, 1932, and subsequently issued as Patent No. 1,965,534, granted July 3, 1934.

What is claimed is:

1. In a device of the class described, a central electrode, a core of insulating material around said central electrode, said core having a shoulder intermediate its ends, a second insulator surrounding, but spaced from, said core, a heating coil in the space between said core and second insulator, and means resting on said shoulder to electrically ground one end of said coil.

2. In a device of the class described, the combination with a grounded shell having an internally disposed shoulder, of a central electrode having an insulator thereon, extending to a point near its lower end, a cylindrical electrode surrounding said insulator and supported by the shoulder on said shell, and a heating coil also surrounding said insulator and having one end electrically connected with said cylindrical electrode, there being electrical contact between said cylindrical electrode and shell at a region above said shoulder.

EDWARD B. NOWOSIELSKI.
